UNITED STATES PATENT OFFICE.

GEORGE W. BROWN, OF CAPE ELIZABETH, MAINE, ASSIGNOR TO SUSAN J. DODGE, OF NEW-CASTLE, MAINE.

DESIGN FOR A COMBINATION HEATING AND LIGHTING STOVE.

52,520.

Specification for Design.

Patented Oct. 8, 1918.

Application filed March 27, 1918. Serial No. 225,134. Term of patent 7 years.

To all whom it may concern:

Be it known that I, GEORGE W. BROWN, a citizen of the United States, residing at Cape Elizabeth, in the county of Cumberland and State of Maine, have invented a new, original, and ornamental Design for Combination Heating and Lighting Stoves, of which the following is a specification, reference being had to the accompanying drawing, forming part thereof.

The figure is an elevation of a combination heating and lighting stove showing my new design.

I claim:

The ornamental design for a combination heating and lighting stove, as shown.

GEORGE W. BROWN.
